[57] CLAIM

The ornamental design for a scissors display cabinet, as shown and described.

DESCRIPTION

FIG. 1 is an exploded front perspective view of a scissors display cabinet showing my new design; the broken lines are for illustrative purposes only;

FIG. 2 is a reduced-scale rear elevational view thereof with the lid portion in position on the base;

FIG. 3 is a left end elevational view as seen when in use;

FIG. 4 is a bottom plan view thereof; and

FIG. 5 is a sectional view taken along line 5—5 of FIG. 1.

FIG. 5

FIG. 4

FIG. 1

FIG. 2

FIG. 3
